DESIGN FOR A HAIR DYEING TRAY

Ashley Carawan, Chicago, Ill.

Application April 6, 1939, Serial No. 84,093

Term of patent 7 years

To all whom it may concern:

Be it known that I, Ashley Carawan, a citizen of the United States of America, residing at Chicago, county of Cook, and State of Illinois, have invented a new, original, and ornamental Design for a Hair Dyeing Tray, of which the following is a specification, reference being had to the accompanying drawing forming part thereof, wherein:

I claim:

The ornamental design for a hair dyeing tray, as shown.

ASHLEY CARAWAN.
